UNITED STATES PATENT OFFICE.

GEORGE C. FRYE AND FRED C. ROLLINS, OF PORTLAND, MAINE.

ASEPTIC RAZOR-STROP AND DISPENSER.

1,137,599.

Specification of Letters Patent. Patented Apr. 27, 1915.

Application filed January 15, 1915. Serial No. 2,335.

To all whom it may concern:

Be it known that we, GEORGE C. FRYE and FRED C. ROLLINS, citizens of the United States, residing at Portland, in the county 5 of Cumberland and State of Maine, have invented certain new and useful Improvements in Aseptic Razor-Strops and Dispensers, of which the following is a specification.

10 Our improvement relates to aseptic razor strops and dispenser therefor. It is specially designed to be used in barber shops in the place of strops now in common use, which are used repeatedly and are therefore 15 likely to become insanitary.

The object of our invention is to provide a strop of such material and in such form that a portion may be used and then separated and thrown away, a fresh portion being used for each customer.

Another object is to provide a convenient dispenser for the strop.

We have illustrated in the drawings what at present seems to be the preferred embodiment of our invention.

In the drawing herewith accompanying and making a part of this application, Figure 1 is a perspective view of our improved strop dispenser showing a portion of the 20 strop; Fig. 2 is an end elevation of the same and Fig. 3 is a vertical section of the same.

Same reference characters indicate like parts in the several figures.

In said drawing A is a suitable container 35 for the strop, B a door to admit the roll C of strop material which is in the form of a continuous ribbon of flexible material and may or may not be treated with a fine buffing material or a mild abrasive like crocus 40 flour. The free end of the strop material projects through a slot D in the container. Adjacent and above the slot is a stop E. The container is provided with a cutter E' which may be formed on the top edge of the 45 stop. Pivotaly attached to trunnions F in the ends of the container is a clamping lever designated as a whole by the character G. This lever has a locking bar H extending across the container below said slot and a 50 locking bar operating arm I spaced apart from and under the bar H and having an open end J to admit the strop sidewise thereunder. The apparatus may be attached to a table, shelf or wall in any convenient manner. As shown it has a clamp-

ing jaw K and a set screw L. It should be mounted about hip high.

The operation of our improved device is as follows: The roll of strop material is placed in the container, its free end projecting through the slot provided therefor and between the stop and said locking bar. The barber takes hold of the projecting free end of the strop, draws it out a sufficient distance, then places it under the lever arm 65 and holding it firmly draws it upwardly against said arm which raises the arm and with it the locking bar and on account of the great leverage presses the locking bar and the strop material against the stop with 70 sufficient force to hold it from running out while the razor is being stropped. After the razor is stropped the portion used is removed from under the lever and brought up in contact with the cutter E', and severed 75 from the roll and discarded. These operations may be repeated until the roll of material is exhausted, when a fresh roll may be placed in the container. By our improved method the razor never comes in contact 80 with an insanitary strop.

Having described our invention and its uses, we claim:

1. A magazine razor strop comprising a long narrow flexible ribbon of any suitable 85 stropping material made into the form of a roll and means for dispensing it comprising a container with a narrow opening for dispensing the strop, a stop on one side of said opening and a pivoted bar on the other side 90 of said opening and means operable by the free end of the strop to lock the strop temporarily between said stop and bar.

2. A magazine razor strop comprising a long narrow flexible ribbon of any suitable 95 stropping material made into the form of a roll and means for dispensing it comprising a container provided with a long narrow opening for dispensing the strop, a stop and cutter on one side of said opening and a pivoted locking bar on the other side of said opening and means operable by the free end of the strop to lock the strop temporarily 100 between said stop and bar.

3. A magazine razor strop comprising a long flexible ribbon of any suitable stropping material made into the form of a roll and means for dispensing it in convenient portions comprising a container provided 105 with a long narrow opening for dispensing 110

the strop, a stop along the edge of said opening and a locking bar pivotally attached to the ends of the container having a transversely extending bar adapted to lock the strop against said stop and a lever arm substantially parallel with said bar and having a free end adapted to let the strop in and out sidewise.

In testimony whereof we affix our signatures in presence of two witnesses.

GEORGE C. FRYE.
FRED C. ROLLINS.
